APPARATUS FOR FORMING PRINTING SHEETS IN PREPARATION
FOR APPLICATION TO A PRINTING CYLINDER

Filed June 28, 1924

Patented May 4, 1926.

UNITED STATES PATENT OFFICE.

MALCOLM OWEN, OF LONDON, ENGLAND.

APPARATUS FOR FORMING PRINTING SHEETS IN PREPARATION FOR APPLICATION TO A PRINTING CYLINDER.

Application filed June 28, 1924. Serial No. 723,038.

To all whom it may concern:

Be it known that I, MALCOLM OWEN, a subject of the King of Great Britain, residing at 109 Farringdon Road, London, E. C. 1, England, have invented certain new and useful Improvements in Apparatus for Forming Printing Sheets in Preparation for Application to a Printing Cylinder, of which the following is a specification.

10 This invention relates to apparatus for forming sheets in preparation for application to a printing cylinder of the kind having a gap in which the ends of the sheet are secured, in particular to the forming of 15 etched thin sheets of metal which are applied to cylinders for intaglio and photogravure printing.

Such etched sheets are of very springy nature, and accordingly very difficult to manipulate. However, in Patents No. 1,458-20 477 and No. 1,478,947 there is described and claimed a method and apparatus respectively for applying sheets directly to their printing cylinders, the method consisting in attaching one end of the sheet on one side of the 25 gap of the printing cylinder, and stressing the sheet mechanically under tension tangentially to the cylindrical surface, the cylinder being held against rotation during the initial 30 straining, and then while the strain is maintained, rotated to wrap the sheet tightly around it, whereon the other end of the sheet is fixed within the gap. By such a process the sheet is found to be absolutely evenly 35 bedded on the surface of the printing cylinder.

In printing it is always necessary to provide a proof, and accordingly labor and time are lost in applying the sheet to the printing 40 cylinder in order to take off one or a few prints, because this necessitates the removal of the cylinder from the printing machine in order to be put into the apparatus, operating as described above, so as to apply the sheet thereto, and then replace the cylinder with the sheet in the printing machine. The 45 proofs having been taken, the sheet is removed so as to leave the cylinder applicable for other printing processes.

50 In order to avoid the necessity of removing the cylinder of a printing machine, it has been proposed by this applicant in application Serial No. 692,409 to previously form the sheet on a segmental former so 55 that when taken therefrom it is ready for im-

mediate application to the cylinder, the ends of the sheet fitting the walls of the gap, the method of forming the sheet consisting in cutting the sheet to correct length, stressing the sheet, and while the stress is maintained, bending the sheet over sharp edges of the segmental former spaced apart by a convex segmental surface thereof, which surface is of a length equal to the circumference of the printing cylinder less the width of the 60 gap, so that as a continuous operation first one end of the sheet is folded over and the sheet bent, and then the other end folded over, the spacing and forming of the fold being such that it will coincide exactly with 65 the longitudinal edges of the cylinder gap when the sheet is applied to the cylinder.

In the accompanying drawings is illustrated a preferred construction of apparatus according to the present invention.

Fig. 1 is a side elevation of the unit apparatus;

Fig. 2 is a plan view of the construction shown in Fig. 1 with parts removed and parts in section for sake of clearness;

Fig. 3 is an enlarged view of a detail comprising the construction shown in Figs. 1 and 2; and

Fig. 4 is a side elevation of a segmental former designed to be used with a cylinder 85 in which the walls of the gap are at right angles to the horizontal diameter of the cylinder for only a part of the height of the gap, and then diverged so that the outer part of the gap is tapered toward the centre of 90 the cylinder. This form of cylinder is used with a wedging piece which fills the gap and secures the ends of the sheet within it.

As this cylinder construction forms no part of the present invention no further description will be given thereof.

Referring to the drawings 1 indicates the former, which is hereafter more fully described, upon which it is desired to wrap a metal printing sheet under tension. The former runs in bearings 2 on the support including framework 3, on which is mounted uprising supports 3^a, and its rotation is effected by a train of driving pinions and driven wheels e. g., 5, 6, 7, 8, the first pinion 100 5 being rotated by a pulley 9 or the like. By reason of the gear ratios, unless rotated by the pulley 9, the proportions are such that the former 1 will be held stationary against 105 rotation even though subjected to a consider- 110

able tension along the line 11 (Fig. 1), which indicates the line of pull tangentially to the former along which the sheet is stressed when the former is rotated with the 5 tension applied. The sheet 10 (Fig. 2) itself is connected by means of a cable 12 with a rotatable member 13 in the form of a pulley about which the cable may be coiled, which in turn is connected with friction 10 drums 14, 15 riding loosely on shaft 16 and having the drum 15 fixed to spur wheel 17, the latter in gear with pinion 18 on an intermediate parallel shaft 20, these shafts 16 and 20 being carried in bearings on the 15 supports 3^a, and, therefore, at a fixed distance from the bearings 2 aforesaid. The pinion 18 is turned by means of hand wheel 19, and, when free, the driving pulley 13 can therefore, be rotated by the action of 20 the gear pair 17, 18 connected thereto.

The means by which friction is applied to drums 14, 15 to strain the sheet 10 when secured to the former 1 includes a pair of weighted levers 21, 22 carrying weights 23, 25 24 and provided at their opposite ends with sleeves 25, 26 respectively having extensions 27, 28 upon which are keyed operating levers 29, 30 extending downwardly from the said sleeves so as to be within reach of a treadle 30 mechanism 31 which will be described hereafter.

As shown in dotted lines in Fig. 1, and referring only to the weight lever 22, (as the lever 21 is identically arranged and associated) the connection between the lever 22 and the brake drum 15 is achieved by a lever or crank 40 fixedly mounted on the lever 22 at one end of a given diameter of the drum 15 and connected by means of 40 links 41, 42 with arms or straps 43, 44 which partly encircle the drum 15; when allowed, these arms 43, 44 are drawn tightly on, and embrace, the drum 15 by the weight on the lever 22 drawing together the links and consequently the arms to prevent rotation of 45 said drum; the arms are hingedly connected by means of a link 45 at the other end of the said given diameter.

In order that the apparatus may be easily 50 controlled by one operator an arrangement including treadle gear is provided by which the friction applied to the brake drums 14 and 15, through the weight levers 21 and 22, is regulated.

55 The treadle gear consists of the treadle 31 attached to a cross spindle 32, a pair of arms 34 attached to a second cross spindle 33 and provided with rollers 34^a disposed so as to bear on the ends of the levers 29, 30 60 and to depress same under certain circumstances. The connection between the shafts 32 and 33 is preferably made by the levers 35, 36 and the link 37, see Fig. 1, but obviously may be by wheel and pinion.

65 Referring now to the construction shown

in Fig. 4 a former of segmental section as described in my co-pending application Serial No. 692,409, is shown comprising a convex surface 50 which is equal in length to the circumference of the printing cylinder to which the sheet, when formed, is to be applied less the width of the gap. At the ends of the convex surface there are inclined flat faces 51, 52, each forming an edge with the convex surface, and each disposed to include between it and the convex surface an angle equal to the angle between the cylindrical face of the cylinder and the contiguous part (the tapered part) of the walls of the gap, and these faces 51, 52 are equal in length to the tapered parts of the said walls. Each face 51, 52 terminates at the end away from the convex surface in a flat face 53, 54 respectively making edges therewith, and these faces 53, 54 are set at an angle to the contiguous faces 51, 52 respectively so that the angle included between them is equal to the angle between the tapered part of the wall and the contiguous vertical part of the wall of the gap.

90 In operation the treadle 31 is depressed which causes, through the agency of the rollers 34^a, depression of the release levers 29, 30, having the cranks 40 fixedly associated with their upper ends, are sufficiently tilted as to open the respective arms 43, 44 by the action of the respective links 41, 42 connected between the cranks and the arms, thereby retracting the arms and removing the retarding friction from the drums 14, 15 leaving them free to rotate, it being understood that the weighted levers 21, 22 are also lifted. At this moment rotation of the hand-wheel 19 actuating the pinion and wheel 18, 17 is available to rotate the driving pulley 13. If then the sheet 10 is connected by means of the cable 12 with the driving pulley 13 the latter can be rotated, and the other end of the sheet attached to the face 54 of the former, assuming it is placed in its bearings in the position shown in Fig. 4; the cable is wound up on the pulley 13 and eventually a preliminary tension is applied to the cable and the sheet, so that all play on its connecting pins and the like and some part of the slack in the sheet may be removed before the sheet is subjected to the tension proper due to the rotation of the former 1 against the friction applied by the weighted levers 21, 22 on releasing the treadle 31. Besides the saving of time, therefore, the travel of the weighted levers 21, 22 is confined within small limits and a considerable convenience results.

115 In the machine illustrated, the board 47 (Fig. 1) is provided merely for the sheet and the clamping tackle 48 to rest on before the tension is applied.

120 It will be understood that a sheet having 130 been wound on the former 1 under tension is

then in proper condition for applying to the printing cylinder (having a periphery equal in length to the convex surface of the former) on the printing machine proper.

5 The means of connecting the sheet to the face 54 of the former will correspond to the manner of connecting the similar end of the sheet in the wall of the gap. Supposing, therefore, pegs are used in the cylinder gap, 10 similar pegs 55 will be formed on the face 54, in which case the sheet has to be slotted in order that the pegs may form anchors for the sheet on the face 54.

The faces 51 and 53 of the former may be 15 formed on an integral part thereof, or may be comprised in an interchangeable part 56 (as shown in Fig. 4), which includes part of, or is a continuation of, the convex surface 50 of the former. By using an interchangeable part, such as 56, the effective length of the convex surface of the former may be varied by substituting a portion having a different length of continuation surface, so that the said former may be used in the 25 preparation of sheets for cylinders of various diameters.

By substituting weights of different sizes for the weights 23 and 24 the friction on the drums 14 and 15 may be adjusted.

30 The result of using the present invention is that instead of needing to move a cylinder and sheet from the mill only the sheet thereon need be moved for printing or other purposes, and a unit apparatus is obtained in 35 which a printing sheet can be completely formed in preparation for applying it to a printing cylinder.

I claim:—

1. Apparatus for forming printing sheets in preparation for application to a printing cylinder having a gap comprising the combination with a support, of bearings on the support, a former of segmental section rotatably carried by the bearings the convex surface of said former terminating at each end with a sharp edge, the convex surface being equal in length to the circumference of the printing cylinder less the width of the gap, gearing for rotating said former, a tensioning device fixed on the support and spaced from the bearings, fastening means for attaching one end of a printing sheet to the tensioning device, anchoring means for detachably connecting the other end of said sheet near one sharp edge of said former, and means for preventing reverse rotation of said former under effort from the tensioning device, the arrangement being such that on rotation of the said former through 360° the sheet is wrapped thereon and both ends are bent over the sharp edges thereof, whereby the ends of the sheet are ready for immediate fixing in the gap of the said printing cylinder.
2. Apparatus for forming printing sheets in preparation for application to a printing cylinder having a gap comprising the combination with a support, of bearings on the support, a former of segmental section rotatably carried by the bearings the convex surface of said former terminating at each end with a sharp edge, the convex surface being equal in length to the circumference of the printing cylinder less the width of the gap, gearing for rotating said former, a tensioning device including a rotatable member carried by said support at a fixed distance from the said bearings, a brake drum carried by said rotatable member, adjustable friction means operating with said brake drum, connecting means having one end fixed to said rotatable member and adapted to be coiled thereon and at the other end fastening means for attachment to one end of a sheet to be wrapped on a cylinder, anchoring means for detachably connecting the other end of said sheet near one sharp edge of said former, and means for preventing reverse rotation of said spindle under effort from said tensioning device, the arrangement being such that on rotation of the said former through 360° the sheet is wrapped thereon and both ends are bent over the sharp edges thereof, whereby the ends of the sheet are ready for immediate fixing in the gap of the said printing cylinder.
3. Apparatus for forming printing sheets in preparation for application to a printing cylinder, comprising the combination with a segmental former, of a rotatable member spaced parallelly therefrom, means for connecting one end of the sheet to the segmental former and means for connecting the other end thereof to the rotatable member, for straining the sheet between said former and member, manual means for turning said member for applying an initial strain to said sheet, a friction brake drum movable with said rotatable member, straps co-operating with said drum, weights for applying said straps to said drum, a treadle and operating lever for retracting the straps from said drum, means for preventing reverse rotation of said former under strain from said tensioning device, and gearing for rotating said former when said straps are applied, whereby on rotation of said former through 360° a sheet wrapped thereon has its ends formed ready for application to a printing cylinder.
4. The combination with a rotatably mounted segmental former having means for removably connecting one end of a sheet thereto, of a wheel member, means wound thereon forming part of a connection between the wheel and the other end of the sheet, the wheel member being spaced from said former to permit the sheet being strained between them, a friction brake, including a drum and a pair of hinged straps,

associated with said wheel, a rocking shaft, links pivotally connected to said shaft, and to the free ends of said brake straps, a weighted bell crank pivoted by said rocking shaft, said weight acting to rock the shaft so as to apply the straps to the brake, and treadle gear for tilting said bell crank against said weight, thereby rocking the shaft to retract the brake straps, means for 10 rotating said former against said friction brake, and means for preventing reverse rotation of said former, whereby on rotation of said former through 360° a sheet wrapped thereon has its ends formed ready for application to a printing cylinder.

5. A rotatable segmental former for preparing a printing sheet for immediate application to a printing cylinder, having a gap, the walls of the gap diverging at the 20 outer part thereof, comprising a convex surface of a length equal to the circumference of the printing cylinder to which the sheet

is to be applied, less the width of the gap, a flat surface contiguous to the convex surface at each end thereof forming an edge with the convex surface, the flat surfaces each including between them and the convex surface an angle approximately equal to the angle between the cylindrical face of the printing cylinder to which the sheet is to be applied and the contiguous part of the walls of the cylinder gap, each said flat surface terminating at the end away from the convex surface in a second flat surface, each set to its contiguous flat surface at an angle equal to the angle contained between two such surfaces in the walls of the gap of the printing cylinder to which the sheet is to be applied, and connecting means on one of said second flat surfaces for attaching one end of a printing sheet thereto.

In testimony whereof I affix my signature.

MALCOLM OWEN.
